UNITED STATES PATENT OFFICE

2,499,189

STOKER BURNER HEAD WITH ROD MEANS
TO ANCHOR TUYÈRE BLOCKSHenry R. Geary, East Orange, N. J., assignor to
General Electric Company, a corporation of
New York

Application December 13, 1947, Serial No. 791,546

2 Claims. (Cl. 110—44)

1.

The present invention relates to stokers, particularly the tuyère and plenum base assembly forming the burning head.

One object is to provide an improved form of sectionalized tuyère suitable for automatic coal stokers and capable of producing adjacent rows of finely divided streams of air of equalized velocity and directed slightly downwardly and oppositely into the fuel bed from surrounding juxtaposed arched tuyère elements.

An additional object is to provide associated diverging air streams to promote rapid combustion of fuel moving out of the fuel bed over the arched tops of the tuyère elements into the clinking zone.

Another object is to provide an improved form of tapering tuyère element of relatively low heat storage mass and having a sharply rounded ridge top and oppositely sloping front and back walls and a central mounting web extending therebetween to form divisive airflow channels tapering upwardly to rows of air discharge slots provided in the upper edges of the walls so as to concentrate the combustion in the upper part of the fuel bed with minimum heating of the green fuel during both fuel feed operation and shutdown.

Another object is to provide a burning head for a stoker with an improved plenum base having a cleanout door and both coal and air supply lines removably connected therewith and having improved means for removably mounting opposite rows of tuyère elements in alignment thereon to provide a rectangular upwardly expanding fire bed.

Other objects and advantages of the invention will appear in the following description of the accompanying drawing in which Fig. 1 is a sectional view of a stoker burning head embodying the improvements of the present invention in a preferred form; Fig. 2 is an end view showing more clearly the coal feed and air supply pipes and cleanout door symmetrical connection in the plenum base of the burning head of Fig. 1; Fig. 3 is a top view, partly in section, showing the rows of juxtaposed tuyère elements mounted on the plenum base between the corner anchoring tuyère elements around a rectangular coal feed throat or opening formed centrally in the top of the base with the tuyère elements communicating with the air slots provided adjacent each side of the rectangular opening; Fig. 4 is a perspective view of the improved form of tuyère element with a mounting rod extending therethrough; and Fig. 5 is a perspective view of the corner tuyère element that anchors each end of the mounting rod.

2.

As shown in Fig. 1, the improved plenum base 10 for the tuyères preferably is cast as a unit and provided with an internal coal feed passage in the form of a cylindrical to rectangular transition elbow tube 11. The cylindrical portion 12 receives the delivery end of the coal feed screw 13 that conveys the coal through the coal feed pipe 14. The feed pipe 14 is carried by a plate 15 that is removably secured to one side of the plenum base 10 and may be connected together with the coal feed pipe 14 to an automatic stoker mechanism, not shown. The upwardly flaring cylindrical-to-rectangular transition outlet 16 of the elbow tube 11 serves to quickly divert the horizontal flow of coal vertically upwardly with minimum degradation and segregation.

The coal feed elbow tube 11 extends centrally through the plenum base 10 from one side to the top thereof and is surrounded by the plenum air chamber 17 so as to maintain the coal passing therethrough relatively cool. Air under pressure is supplied to the plenum chamber 17 through a triangularly shaped air supply pipe 18 that is carried by the removable plate 15 in fixed alignment with the coal feed pipe 14. The removable plate 15 also carries a separately removably triangularly shaped cleanout door 19 symmetrically located in reversed relation with the triangularly shaped air supply pipe 18 so that the coal feed pipe 14 is nested therebetween. The cleanout door 19 provides access to the plenum chamber 17 for removing any accumulated ash, riddlings and the like. The plate 15 is removably secured to base 10 by bolts 20 so that the air supply pipe 18 communicates with the plenum chamber 17 through the triangularly shaped opening 21 formed in the side of plenum base 10 and the separately removable cleanout cover 19 communicates with the plenum chamber 17 through the triangularly shaped opening 22 oppositely formed in the side of base 10. The plenum chamber 17 also is in communication with the interior of the coal feed tube 11 through a restricted hole 23 so as to pressurize the tube 11 sufficiently to prevent backflow of combustion gases.

An upwardly expanding rectangular fuel bed is provided for the active combustion of the fuel above the fuel feed opening 24 by opposite rows of juxtaposed tapering tuyère elements 25 in conjunction with the sloping curved corner tuyère elements 26. Each tuyère element preferably is cast of a high chromium silicon alloy to increase the resistance to scaling and oxidation. Each intermediate tuyère element 25 is arched so as to straddle the air discharge slots 28 formed in

the top of the plenum base 10 adjacent each side of the rectangular fuel feed opening 24 therein. As shown in Figs. 2 and 3 each corner tuyère element is removably mounted on top of the plenum base 10 by a screw 29 that engages with a suitably threaded hole 30 and serves to anchor the ends of the mounting rods 31 that extend through the adjacent rows of tuyère elements 25.

As most clearly shown in Fig. 4 each tuyère element 25 is provided with a sharply rounded ridge top 35 having the steeply sloping front and broken slope back walls 36 and 37 extending therefrom to form a hunchbacked arch. A transverse web 38 extends between the oppositely sloping front and back walls of the tuyère 25 so as to form a juxtaposed pair of upwardly tapering airflow channels 39 and 40 on opposite sides of the web 38. A downwardly tapering opening 38' is provided in the web 38 for receiving the mounting rod 31 therethrough to effect self alignment of the adjacent tuyère elements and also for providing progressively unrestricted communication between the airflow channels 39 and 40. Opposite pairs of downwardly inclined air discharge slots 44 and 45 are formed in the upper edges of the front wall 36 and a pair of oppositely directed restricted airflow channels 46 and 47 are formed in the upper edges of the broken slope back wall 37 to supply sufficient air for completing combustion of the fuel passing over the round ridge top 35.

In mounting the tuyère elements 25 and 26 on the top of the plenum base 10, the number of edgewise slotted tuyère elements 25 required to form a side of the desired length for the rectangular fuel bed are aligned in a row and the mounting rod 31 extended through the opening 38' formed in the central mounting web 38 of each element. The protruding ends of the mounting rod 31 are then inserted in the anchoring socket 32 of the adjacent corner elements 26. When the tuyère elements are thus assembled, the flanges 33 formed at the sides of the corner tuyère element 26 serve to close the adjacent airflow channels of the adjacent tuyère blocks and the curved ridge top 34 serves to interconnect the round ridge tops 35 of the adjacent rows of tuyère elements 25. In this way each row of edgewise slotted tuyère elements 25 is readily mounted on the top of the plenum base 10 by tightening the holdown screws 29 for the corresponding corner tuyère elements 26. The juxtaposed tuyère elements 25 on rod 31 are self-adjusting into straddling alignment with the corresponding air discharge slot 28 to bring each airflow channel 39 and 40 and slots 44, 45, 46 and 47 on opposite sides of the mounting web 38 into registering alignment and in communication with the plenum chamber 17 and thus insure a substantially equalized distribution of the combustion air thereto. Furthermore, the perforate web of each element provides for interconnecting the adjacent airflow channels of the adjacent blocks therethrough so as to tend to equalize the supply of air between the multiplicity of air discharge slots in case any of these slots should become clogged or plugged during operation of the stoker. However, the downward inclination of the slots formed in the front wall of each tuyère element tends to prevent en-

trance of ashes or riddlings into the interior of the tuyère elements and the location of the air slots 28 directly therebelow serves to prevent any accumulation of ash or riddlings inside thereof. 5 The removable cleanout door enables ready removal of any accumulation of ashes or riddlings falling through the air slots 28 into the plenum chamber 17.

The round ridge tops 35 of the tuyère elements 25 with the oppositely sloping walls 36 and 37 extending therefrom serve to separate the active combustion fuel bed surrounded by these elements from the surrounding clinkering zone for completing combustion of the coal and fusion of the ash. Due to the tapering arched shape of the tuyère elements 25 there is a minimum of heat stored in these elements during stoker idling periods. Furthermore, during stoker operation the round ridge top 35 of the tapering tuyère elements 25 are effectively cooled by the air passing upwardly through the side channels 39 and 40 to the slots 44, 45 and 46 located in the upper part of the front and back walls adjacent to the top 35.

What I claim as new and desire to secure by Letters Patent of the United States is:

1. A stoker burning head having in combination a plenum base provided with a rectangular fuel feed opening and an air supply slot at each side of said opening, tuyère corner blocks, each mounted on said base adjacent a corresponding corner of said opening, and opposite rows of juxtaposed tuyère blocks, each row having a mounting rod extending therethrough for engaging with adjacent corner blocks to mount said row of tuyère blocks therebetween in communicating alignment with a corresponding air supply slot.

2. A stoker burning head having in combination a plenum base provided with a fuel feed opening, corner anchor blocks, each arranged on said base adjacent a corresponding corner of said opening, a row of juxtaposed tuyère blocks arranged on each side of said opening intermediate corresponding pairs of said corner anchor blocks, an anchoring rod extending through each row of said tuyère blocks and anchored in the corresponding pair of said corner anchor blocks, means for attaching said corner anchor blocks to said base to secure said tuyère blocks in alignment to said base, and means for supplying air under pressure from said base to said tuyère blocks.

HENRY R. GEARY.
